UNITED STATES PATENT OFFICE.

JAMES SCHUYLER, OF FINDLAY, OHIO.

TURN-TABLE.

SPECIFICATION forming part of Letters Patent No. 254,165, dated February 28, 1882.

Application filed December 9, 1881. (No model.)

To all whom it may concern:

Be it known that I, JAMES SCHUYLER, of Findlay, in the county of Hancock and State of Ohio, have invented certain new and useful 5 Improvements in Turn-Tables; and I do hereby declare that the following is a full, clear, and exact description of the invention, which will enable others skilled in the art to which it appertains to make and use the same, reference being had to the accompanying drawings, which form a part of this specification.

My invention relates to turn-tables for rail-road-cars, engines, &c.; and it consists, first, in a bed divided into two inclined planes upon 15 which are secured the track-rails curved to fit the inclines.

It further consists in a table having two flanged wheels at each outer end, two or more central unflanged wheels, and a shaft or bolt 20 rigidly secured to the center of the table and entering a pipe and cone in the center of the bed to guide the bed in its ascent and descent on the inclined bed.

It further consists in details of construction 25 that will be more fully set forth in the specification and claims and pointed out in the accompanying drawings, in which—

Figure 1 is a perspective view of my device; Fig. 2, a plan view, and Fig. 3 a vertical section of same.

Referring more particularly to the drawings, A indicates the base, which may be of concrete, rubble, stone, heavy timbers, or a floor of plank. Upon this lay a sufficient number 35 of ties of varying thickness to give the desired inclination diverging from the center block, E, which may be of wood, stone, or iron. Upon these ties I spike the rails C D, which are curved to fit the inclined sides B B', which, as 40 shown in Figs. 1 and 3, are inclined planes. The center block, E, is for the support of the vertical cylinder or pipe F. These parts are intended to be stationary. Secured to the center of the table is a shaft or bolt, H, about 45 three inches in diameter and six feet in length, that passes down through the vertical pipe and cone at the bottom. At each opposite end of the table G are two flanged wheels, I, traveling on the outer rails, C, and on opposite 50 sides of the shaft H are two or more unflanged wheels, K, which travel on the central rails, D.

These wheels are about two feet in diameter; but may be of any convenient size, and are secured to the table in any convenient way. The number of wheels may vary according to the 55 length of the table. The circumference of the large circle under the table is one hundred and twenty-six feet, the diameter thirty-nine feet three inches, the diameter of small circle thirteen feet one inch. The table is intended to 60 be forty-three feet long over all, and about four feet high from the rail-circle, and the chords about four feet apart, with plank twelve feet long spiked across the top of the chords, on which the rails will be fastened that the engine will stand on while the table is carrying 65 it around until it meets the track to run off on. Then the table is turned back empty to the high point to take another load around to the low point. The table is adapted to turn about 70 half a circle on each inclined plane, and its particular utility exists in shifting the load from the higher-level track to the lower-level track. The high point on each side B B' will be about twelve inches above the low point, 75 but can be varied as desired. The table G, when finished, has a floor of plank twelve inches long by two inches thick fastened across on top of table-chords.

It will be observed that one end of each side 80 B B' is elevated above the other, and the elevated end of one side, B, is adjacent to the lower end of the opposite side, B'. At these low points I may have suitable buffers, P, to take up the force of the weighted table when 85 it reaches the lowest or stopping point. The object of this form of construction of table and bed is to cause the wheels of the table to travel on a descending grade when loaded and on an ascending grade when not loaded, so that when 90 a table is loaded with a forty or fifty ton engine the weight of the load will assist in making the turn. The table is intended to be level at any point it may be on. The planes, each 95 of which forms a half-circle, are inclined in opposite directions, while the central portion or block, E, is in a single horizontal plane. As the table travels from the higher to the lower point but little if any force is required to move it.

The table may be furnished with suitable 100 stop or brake mechanism, so as to stop it at

any desired point on the incline to meet tracks which are graded and run to conform to the level of the table-tracks.

Having thus described my invention, what I claim is—

1. A track-bed for railway turn-tables, consisting of two inclined planes, each of which forms a half circle and inclined in opposite directions, and provided with tracks curved and so inclined with the face of the plane to which they are secured, substantially as shown and described, and for the purpose set forth.

2. A track-bed for railway turn-tables, consisting of two inclined planes provided with an exterior and interior track, as described, and a cone and pipe secured to said bed and adapted to receive a guide-shaft secured to the center of the table, substantially as shown and described.

3. A turn-table provided with outer flanged wheels and inner unflanged wheels, and adapted to travel on tracks secured to inclined planes in such manner that the table will be level at any position, substantially as and for the purpose set forth.

4. The combination of the bed A, having the inclined surfaces B B', tracks C D, cone F, and pipe F', with the table G, provided with wheels I K, and shaft H, substantially as described, and for the purpose set forth.

In testimony that I claim the foregoing as my own I have hereto affixed my signature in presence of two witnesses.

JAMES SCHUYLER.
